(57) **CLAIM**

The ornamental design for a four row seven day pill box, as shown and described.

DESCRIPTION

FIG. 1 is a top, front and right side perspective view of a four row seven day pill box showing our new design;

FIG. 2 is a top, rear and left side perspective view thereof;

FIG. 3 is a top and left side perspective view thereof;

FIG. 4 is a front view thereof;

FIG. 5 is a rear view thereof;

FIG. 6 is a left side view (viewer's perspective) thereof;

FIG. 7 is a right side view (viewer's perspective) thereof;

FIG. 8 is a top view thereof; and,

FIG. 9 is a bottom view thereof.

It is noted that any broken line illustration of environmental structure in the drawings is not part of the design sought to be patented.

The broken lines depict portions of the four row seven day pillbox that form no part of the claimed design.
